PUMP

Ernest L. Abramson, Davenport, Iowa, assignor
to Westco Pump Corporation, Davenport, Iowa,
a corporation of Delaware

Application September 20, 1933, Serial No. 690,199

4 Claims. (Cl. 103—96)

This invention relates to pumps and more particularly to rotary pumps having an annular pressure building passageway therein.

One of the objects of the present invention is to provide a pressure pump of such construction that the same may be easily converted to a pump of a different capacity without changing the casting thereof.

Another object is to provide a pressure building pump so constructed that removable rings having annular pressure building passageways therein are provided which may be easily removed and replaced with other rings for changing the capacity of the pump.

Another object is to provide a pressure building pump having removable rings forming a pressure building passageway with a divided inlet arrangement for admitting fluid through opposite sides of the pressure building passageway to opposite sides of the rotor.

Another object is to provide a pump with removable rings having a pressure building passageway, that are so arranged that the fluid to be pumped is introduced to opposite sides of the rotor buckets confined within the passageway.

Another object is to provide a pump with operating parts of a material different from the pump casing and so arranged that such material as sewage or acid-like fluids may be pumped without damage to the pump structure.

A further object is to provide a pump having removable rings provided with a pressure building passageway with new and improved means for confining the rings within the pump housing.

With the above and other objects in view, which will be apparent from the following detailed description, the present invention consists in certain features of construction and combinations of parts that will be apparent to those skilled in the art to which the invention appertains.

In the drawings:

Figure 1 is a front elevation of one of the pump constructions of the present invention;

Fig. 2 is a front elevation of the pump illustrated in Fig. 1, the cover plate being removed therefrom and certain portions broken away to show the rotor and pressure building passageway;

Fig. 3 is a longitudinal section taken approximately upon the line 3—3 of Fig. 1;

Fig. 4 is a fragmentary section taken approximately on the line 4—4 of Fig. 2;

Fig. 5 is a section taken approximately on the line 5—5 of Fig. 2, showing the divided inlet after

providing the admission of fluid to opposite sides of the pressure building passageway;

Fig. 6 is an elevation of one of the pump rings taken in a direction looking toward the side having the pressure building passageway therein;

Fig. 7 is an elevation of the opposite side of the pump ring illustrated in Fig. 6;

Fig. 8 is a view of one of the pump rings looking in the direction of arrows 8—8 of Fig. 6;

Fig. 9 is a longitudinal section taken through a modified pump arrangement of the present invention;

Fig. 10 is a front elevation of the pump illustrated in Fig. 9, the cover plate being removed and portions of the rotor being broken away to show the pressure building passageway therein;

Fig. 11 is an elevation of the rear face of one of the pump rings illustrated in Fig. 9;

Fig. 12 is an elevation of the front face of the pump ring illustrated in Fig. 11;

Fig. 13 is a section taken approximately on the line 13—13 of Fig. 12;

Fig. 14 is a transverse section taken approximately on the line 14—14 of Fig. 10, showing the outlet passage and also showing the divided inlet passage;

Fig. 15 is a side elevation of a further modified pump construction, a portion of the same being shown in section;

Fig. 16 is a section of the pump illustrated in Fig. 15 taken approximately on the line 16—16 of Fig. 15; and

Fig. 17 is an elevation of the main pump ring, showing the inlet and outlet passageways therein.

The present invention has to do particularly with pressure pumps having an annular pressure building passageway and a rotor having marginal buckets at opposite sides which lie within the pressure building passage, and it is contemplated to provide such a pump with means where-
in the capacity of the same may be readily changed by merely replacing removable pump rings with other pump rings having a different character of pressure building passageway. By doing this the necessity of providing a number of pumps and pump casings suitable for obtaining different capacities is eliminated since in the present invention it is only necessary to provide a casing of one size with a number of replaceable rings. This materially reduces manufacturing costs of such pumps and also eliminates the necessity of providing storage space for a number of bulky pumps of different capacity.

The present invention also contemplates such

a construction in which the removable pump rings are arranged to have a divided inlet passage for admission of fluid to opposite sides of the pressure building passage.

5 Referring to the accompanying drawings in which like numerals refer to like parts throughout the several views, the pump construction illustrated in Figs. 1 to 8 includes a suitable standard 1 having an annular mounting plate 2 provided with a flange 3. The casing 4 for the pump rings is annular in shape and is provided with a number of lugs 5 which abut and are secured to the mounting plate 2 by means of cap screws 4a or other suitable securing means. The 10 casing 4 is formed with a central bore 4b which is open at the one side and this bore telescopically receives the pump rings 6 and 7, the inner ring 7 of which abuts the web 8 of the casing 4.

The casing 4 is closed in by means of a flanged 15 cover plate 9, a suitable sealing material or packing 10 being disposed between the casing 4 and plate 9 to provide a water-tight seal therebetween.

The cover plate 9 carries a mounting bracket 11 through the medium of a number of bolts or screws 12 threaded into the cover plate. These bolts pass through the arms 13 of the bracket 11 and springs 14 are provided between the heads of the bolts 12 and the arms 13, so that the bracket 15 will have a movement relative to the cover plate 9. Each arm 13 is provided with a finger portion 15 which is disposed to seat back of a lug 16 formed on the casing 4 as indicated in Fig. 3, and the bracket 11 is provided with a central hand screw 17 threaded therethrough to engage with the central portion of the cover plate so that when the finger portions 15 are disposed back of the lugs by rotating the cover plate, the hand screw 17 may be tightened against 20 the cover plate to thereby clamp the cover plate securely against the casing 4 and provide a suitable seal therebetween and clamp the pump rings 6 and 7 between the casing web 8 and the cover plate 9.

45 The casing 4 is formed with an inlet stub 18 and an outlet stub 19 opening through the central bore 4b thereof, these inlet and outlet stubs being disposed substantially at right angles to each other with the passages 20 and 21, respectively, thereof substantially intersecting each other.

Each pump ring is of annular shape and is provided with an annular channel 22 facing the other, which channels, when the rings 6 and 7 are in abutting relation at their peripheries, provide the annular pressure building passageway 23 for the pump.

The base 1 carries suitable journals 1a which carry the pump shaft 24 which extends through the web 8 of the casing 4 and is journalled at its free end 25 in a bearing 26 carried by the cover plate 9.

The pump rotor 27 is slidably mounted on a splined portion of the shaft 24 and extends between the inner peripheries of the pump rings 6, and 7, and has a running engagement therewith. The peripheral edge of the rotor 27 lies within the inlet pump passageway 23 and is provided with a plurality of marginal buckets 28 at its opposite sides.

75 By slidably mounting the rotor on the splined end of the shaft, the assembly of the pump is greatly simplified since no delicate adjustment of the rotor and its shaft is required. The rotor is self centering and runs true because of the

hydraulic balance. Also, any particles of sand or other foreign matter which might enter between the face of the rotor and a side ring will be more quickly dislodged due to the fact that the rotor is permitted a slight longitudinal movement on the shaft.

The channels 22 of the pump rings 6 and 7 extend substantially around the rings and are closed off throughout a narrow extent to provide stops 29 which engage with the sides of the buckets and with the ends of the buckets at 30 to direct the discharge of fluid from the pressure building passage 23 through a port 31 in the edge of the ring into the outlet or discharge passage 21 of the outlet stub 19. 15

In order that the fluid being pumped will be introduced into the pressure building passage 23 at opposite sides of the rotor 27 to provide a more efficient operation of the same, each ring is provided with a recess or groove 32 in its rear face, which recess opens through the radial wall of the annular channel 22, thereby providing an inlet port 33 for each channel 22 adjacent the stop means 29, as viewed in Figs. 5 and 6. The recesses or grooves 32 provided in the outer faces 25 of the rings 6 and 7 are closed in by the casing web 8 and the cover plate 9 and communicate directly with the passage 20 of the inlet stub 18, thus providing a divided inlet, the branches 32 thereof extending at opposite sides of the outlet portion of the annular pressure building passage. 30

In order to properly center the pump rings 6 and 7 with respect to each other, the rings are preferably slotted at 34 to receive a key 35 35 which, when the rings are assembled to the pump casing, holds the rings in proper alignment with each other.

In the construction shown in Figs. 9 to 14, the same features of the invention are employed although in a different arrangement. In this construction the pump casing 40 is formed as an integral part of the supporting standards 41 and the inlet and outlet stubs 42 and 43, respectively, thereof are disposed in directions opposite to each other. The casing 40 is also provided with a central bore 44 which is closed in by a cover plate 45 which is secured to the casing 40 by suitable screws 46. The casing 40 carries a shaft supporting bracket 47 and the cover plate in this construction carries a shaft supporting bracket 48

40 and the rotor shaft 49 extends through both the casing and cover plate and is journalled at its ends in the brackets 47 and 48. Suitable packing glands 50 are provided in the casing 40 and cover plate 45 to form a water-tight seal with the rotor shaft 49. The pump rings 51 and 52, as in the construction previously described, fit closely within the bore 44 and are held in position by means of the cover plate 45. Each ring is provided with an annular channel 53 which combines with the corresponding channel of the other ring to provide an annular pressure building passageway 54 which is closed off at opposite sides of the rotor buckets 55 by a narrow stop means 56. This stop means directs the fluid being pumped through outlet ports 57 in the rings into the outlet passage 58. Each ring is provided in its outer face with a recess 59 which communicates with the inlet passage 60 of the inlet stub 42 and which opens into the pressure building passage through a port 61 provided in the radial wall of the channel 53 of each pump ring. 65

In the construction shown in Figs. 15, 16 and 17, which is especially adapted for the pumping 70

75

of sewage or acid-like materials, the pump rings may be formed of a suitable material that is different from the casing portions. In this construction, the pump includes two annular pump rings 70 and 71, the ring 70 having an annular web 72 and an annular flange 73 extending from the opposite sides of this web. The ring 71 is also provided with a web 74 and with a single flange 75, which extends from one side only of the web and telescopes with the one flange 73 of the ring 70 and which is also provided with a marginal flange 76 that abuts the edge of the flange 73. The two webs 72 and 74 are spaced from each other to have a running engagement with the 15 sides of the rotor 77 and are recessed adjacent the flange 73 to provide an annular pressure building passageway 78. The pressure building passageway communicates with an outlet passage 79 which is provided in a stub 80 that is integral 20 with the flange 73 of the ring 70. The ring 70 is also provided at one side with a cored out inlet recess 81 and with a channel 82 at the opposite side which channel combines with a channel 83 formed in the flange 75 of the ring 71 to provide 25 an inlet recess 84 at the opposite side of the pressure building passageway. These recesses 81 and 84 are disposed at opposite sides of the passageway 78 and open into the same through ports 85 formed in the opposite side walls thereof. 30 The inlet recesses 81 and 84 also communicate with the inlet passage 86 of an inlet stub 87 that is formed integral with the flange 73 of the ring 70 as indicated in Fig. 16. In this construction it will be noted that the fluid enters the inlet 86 35 then divides and passes around the outlet and enters the pressure building passageway at the opposite sides of the buckets of the rotor 77.

The rings 70 and 71 are also provided with central tubular portions 88 which surround the rotor shaft 89 and are provided with packing glands 90 to form a running water-tight seal with the shaft 89.

The rings 70 and 71 are held in assembled relations by means of a pair of casing parts 91 and 92, 45 which are secured together by bolts 93 and which have recessed bosses 94 that receive the tubular portions 88 of the rings. These casing portions 91 and 92 are also provided with brackets 95 within which the ends of the rotor shaft 89 are 50 journaled. These casing portions also provide supporting means for mounting the pump.

In each of the constructions described it will be noted that the casings are so arranged that the pump rings may be readily removed and replaced by other rings in which a pressure building passage having different characteristics is provided.

It will also be noted that in each of these constructions means is provided for introducing the fluid to be pumped into the pressure building passageway at opposite sides of the marginal buckets of the pump rotor so that an efficient construction is provided.

Although several embodiments of the invention

have been herein shown and described it will be understood that numerous details of the construction shown may be altered or omitted without departing from the spirit of this invention as defined in the following claims.

What I claim is:

1. In a rotary pump, a pair of pump rings having mating annular grooves providing an annular pressure building passageway, an outlet for said passageway, opposed inlet ports in opposite sides of said passageway, separate passages for said ports and a common inlet passage for said separate passages, a pair of casing parts secured to each other and holding said rings in assembled relation, a shaft carried by said parts, 10 and a rotor mounted on said shaft and extending between said rings, said rotor having opposed marginal buckets lying within said pressure building passageway, said rings also having tubular extensions surrounding said shaft and packing glands within said extensions and in running engagement with said shaft.

2. In a rotary pump, a pair of pump rings having mating annular grooves providing an annular pressure building passageway, an outlet for said 25 passageway, opposed inlet ports in opposite sides of said passageway, separate passages for said ports and a common inlet passage for said separate passages, a pair of casing parts secured to each other and holding said rings in assembled 30 relation, a shaft carried by said parts, and a rotor mounted on said shaft and extending between said rings, said rotor having opposed marginal buckets lying within said pressure building passageway, said rings also having tubular extensions 35 surrounding said shaft and packing glands within said extensions and in running engagement with said shaft, said casing parts being recessed to telescopically receive said extensions.

3. In a rotary pump, a pair of pump rings 40 having spaced annular webs, one of said webs having a marginal flange extending from a side thereof toward the other web, and the other web also having a circumferential flange telescoped with said first mentioned flange and a radial 45 portion thereon abutting said first mentioned flange, said flanges and webs being annularly recessed to provide an annular pressure building passageway.

4. In a rotary pump, a pair of pump rings having spaced annular webs, one of said webs having a marginal flange extending from a side thereof toward the other web, and the other web also having a circumferential flange telescoped with said first mentioned flange and a radial portion 55 thereon abutting said first mentioned flange, said flanges and webs being annularly recessed to provide an annular pressure building passageway, said rings having an outlet passage for said passageway and separate inlet passages communicating with said pressure building passageway through the opposite sides thereof.

ERNEST L. ABRAMSON.
